UNITED STATES PATENT OFFICE

2,585,135

ADJUSTABLE PATTERN FORMER

Joseph Klakovich, San Pedro, Calif.

Application December 17, 1948, Serial No. 65,884

6 Claims. (Cl. 33—26)

1

This invention relates to pattern projecting and forming devices, and more particularly to a new and improved adjustable template apparatus having means for projecting and scribing a pattern of desired configuration.

Frequently in sheet metal work and the like it is necessary to form a vent or other conduit between two connections having different shaped openings, either in straight-line or offset relationship to one another. Thus, it may be required to form a sheet metal conduit between a square, rectangular, or oblong opening or the like and another opening of like configuration in offset relationship to the first, or to an outlet for opening of different configuration than the first, which may again be in offset or straight-line relationship thereto.

Heretofore, it has usually been necessary to laboriously calculate and lay out a prescribed pattern for forming the desired duct from measurements taken at the job. Frequently the job is located some distance from a shop or layout space or access between such areas is difficult or obstructed.

It is therefore among the objects of this invention to provide a new and improved adjustable template or pattern former of relative compactness and light weight having features of adaptability and ready replaceability of parts, and which is accurate in operation and in use.

It is another object of the invention to provide an apparatus of the desired character described which is susceptible of economic mass production and whose parts are readily adjustable and secure in their adjusted positions.

Another object of the invention is the provision of a new and improved pattern forming apparatus having a plurality of unique and replaceable measuring and scribing means.

Another further object of the invention is to provide a means whereby patterns of complex nature may be directly taken from a site of proposed installation or from measurements and readily transposed to a sheet material or the like for direct fabrication.

Another further object of the invention is the provision in an instrument of the desired character described of a new and improved extensible means for projecting required plane configurations.

Yet another object of the invention is to provide simple, readily replaceable, and easily adjustable means for obtaining critical measurements of spaced openings, offset or not, or at any angle with respect to one another, to and from which it is desired to obtain a pattern.

2

Another specific object of the invention is the provision of a new and improved clamping means, new and improved universally adjustable spacing arm means, and new and improved projecting and scribing elements.

It is also among the objects of this invention to provide a new and improved means of scribing patterns as will be set forth.

It is moreover among the objects of this invention to provide improvements over prior art devices heretofore utilized for a generally similar purpose.

With these and other objects in view, the invention consists in the construction, arrangement, and combination of the various parts of the device whereby the objects contemplated are attained, as hereinafter set forth, pointed out in the appended claims, and illustrated in the accompanying drawings, wherein:

20 Figure 1 is a vertical elevational view, parts being cut away, of an apparatus embodying this invention.

Figure 2 is a sectional view as on a line 2—2 of Figure 1.

25 Figure 3 is a sectional view as on a line 3—3 of the apparatus illustrated in Figure 1.

Figure 4 is an enlarged sectional view as on a line 4—4 of Figure 3.

30 Figure 5 is a detailed view of base members comprising a portion of the optional pattern shaping ends of the apparatus as shown, among other places, in Figure 4.

Figure 6 is a perspective view of the apparatus illustrating a method of its use.

35 Figure 7 is a vertical elevational view as of the upper end of the apparatus illustrated in Figure 1, but showing an optional pattern shaping member substituted thereon.

Figure 8 is a fragmental view as of the lower 40 end of the apparatus of Figure 1 but with longer, tubular, and finger elements substituted thereon.

Referring more particularly to the drawings, an apparatus there illustrated, by way of example and not of limitation, preferably comprises an arm 10 including an outer sleeve 11 and an inner rod 12 longitudinally slidable in telescoping relationship therewith. A slot 14 formed in the upper end of the sleeve 11 permits the end 15 of the sleeve to be pinched on the rod 12 in any desired degree of extension of the latter.

45 A clamp 16 having a threaded leg 17 engageable with a female threaded ear 18 acts through a shoulder 19 engageable with another ear 20 so that upon tightening of the handle 21, the rod 12 and sleeve 11 may be held against relative axial movement.

The upper end of the rod 12 may be formed as with a yoke 21, the opposite legs 22 and 23 of which are pinchable together as by a knurled bolt 24 having a threaded end 25 engageable with corresponding female threads in the leg 22. The bolt 24 may be formed with a shoulder 26 cooperable with the thread 25.

A tongue 28 is formed with a transverse opening 29 through which the threaded end 25 is slideable. Its opposite end forms a threaded bolt 30 which may carry a nut 31, washers 32, and a wing nut or the like 33 in a manner to replaceably hold a disc 35 of any desired diameter. The tongue 28 is firmly and non-rotatably clampable within the yoke 21 by tightening of the bolt 24.

The disc 35 is replaceable upon the bolt 30 by removal of the wing nut 33 and has an opening 36 through which the bolt 30 is slideable.

At its lower end the sleeve 11 may carry a corresponding yoke 40, the lugs 41 and 42 of which are designed to be clamped upon another tongue 43 by means of a knurled bolt 44 having a shoulder 45 and a threaded connection 46 with the leg 42 in a similar manner to the yoke 21.

The tongue 43 may be threaded as at 47 and may be provided with a head 48 extending through openings 49 and 50 in the base or hub members 51 and 52. The head 48 may nest within a corresponding recess 53 formed in the base member 52. A nut 54 provided with a handle 55 may be tightened thereby upon the threads 47 to clamp adjacent cut-out surfaces 56 and 57 of the members 51 and 52 together to prevent relative rotative movement of said members.

The base members 51 and 52 may thus be formed with shoulder portions 58 having any mutually abutting surfaces as 59 formed thereon to limit relative rotation of the parts 51 and 52 to an arc of 90° or other desired angle, i. e., preferably from a position of operative parallelism to one at right angles to one another as will be set forth.

Portions of the hubs 51 and 52 present curved surfaces 60 and 61 confronting corresponding sides of the shoulders 59 in preferred slidable relationship thereto.

The ends 62 of the members 51 and 52 are preferably formed with threaded counterbores as at 63 in opposite directions to accommodate threaded ends 64 of sleeves 65. A bore 66 extends inwardly from and co-axially with the threaded counterbore 63 whereby replaceable fingers 67 may be slidably and extensibly disposed therein and in the bore 68 of said coupling 65.

Tubular elements 70 preferably having a female threaded end 71 and a male threaded end 72 may be threadedly engaged with the corresponding threads 75 of the coupling 65 within a lock nut or chuck 76. The fingers 67 being likewise slidably extensible through the tubular elements 70 and the chucks 76, are clampable by these two latter portions. Thus, slots 77 formed on the male threaded end of the tubular elements 70, in optional spaced parallel circumferential relationship to one another, clamp the finger elements 67 upon the tightening of the chuck 76, thereby limiting to any desired extent the amount of axial extension of the finger members from the chuck, tubular coupling 70, and bore 66 as heretofore set forth.

The fingers 67 may be formed with an axial bore 78 threaded as at 79 for the reception of shanks 80 of replaceable tips 81 provided as with pointed scribing and measuring ends 82. Knurled surfaces 83 and 84 may be provided

upon the tubular elements 70 and the chuck 76 to facilitate manipulation.

Use of the above-described apparatus may be made as follows: Assuming an opening (not shown) from which a sheet metal conduit is to be led and which opening conforms to the diameter of the disc 35, said disc (or another substituted in its place in order to correspond as closely as need be to the opening in question), is positioned therein. Assume further a lower opening (not shown) to which the conduit from the first mentioned opening is to be led is rectangular in shape and axially offset from the first opening in question.

15 The bolt 24 may be loosened permitting the yoke 21 and tongue 28 to be given an angular relationship as illustrated, by way of example, in dotted outline in Figure 1, and is thereupon tightened to retain such angular relationship.

20 The arm 10 may be made to correspond to the distance between the openings by extension of the arm 10, by loosening of the handle 16 and then tightening the same to prevent relative axial elongation or other movement of the arm 10.

25 A corresponding bolt 44 or the like controlling the yoke 40 and tongue 43 may be loosened to permit a corresponding relative offset in the associated parts whereby the lower end of the apparatus may be made to correspond to any angular or parallel aspect of the square opening referred to relative to said round one.

The nut 54 may be loosened by the handle 55 permitting rotation of the members 51 and 52 upon the bolt 85 until the points 82 upon the respective fingers 67 are aligned with the corners of the opening. The nut 55 may be tightened to prevent relative movement of the members 51 and 52. The chucks 76 may be loosened to permit extension of the fingers 67 until the points 82 are disposed in the corners of said opening. Thereupon, the chucks 76 may be tightened or one or more fingers and associated tubular elements of different length substituted as required.

30 The apparatus as above described has now assumed the position of a true template conforming in offset longitudinal distance, size and relative angularity to the projected plane surfaces of the openings between which the desired connection is to be made.

The template, having first been properly positioned and set, is next laid upon a sheet of any desired material 90. A center line 91 may then be drawn midway between adjacent points 82 which latter are preferably forceably impressed in said material.

35 The disc 35 may be marked off in degrees as by any lines 92. In any event, a mark as at 93 may be made upon the material 90 at the point of tangency of the edge 94 of the disc 35 with said material, and a line 95 may then, or subsequently, be drawn between said mark 93 and another mark 96 halfway between points 82 on line 91. The line thus drawn will correspond with one end of a portion, as one-half, of the desired pattern.

40 The apparatus is then rolled in either a clockwise or counter-clockwise direction on the axis thereof to any extent desired, but preferably for one-half a revolution and the corresponding points of rest of any of the points sequentially marked or impressed upon the sheet 90.

45 The edge of the disc which is thereby caused to roll simultaneously upon the sheet 90 is

scribed upon said sheet either by firmly pressing the disc down against the material to make an impression thereon or by continuously tracing its path as with a scribe or pencil.

It will thus be apparent that upon completion of, say, one-half a complete revolution of the apparatus, as by rolling the same, it will be possible (by recording the path of the rectangularly spaced tips 34 and the periphery of the disc, respectively, as stated) to project a pattern which will correspond in plane outline with the desired plane or flattened pattern of a required conduit. The material 90 may then be cut, preferably in halves corresponding to the half-pattern projected by half a revolution of the apparatus, and upon being cut and formed by rolling, creasing and joining of adjacent edges, will conform accurately to a desired conduit which will accurately connect said first and second openings.

It will be seen that the cross-shaped base members and their extensible arms and tips may be disposed relative to one another at any angle so as to conform to a rectangular orifice as well as to a square. It is also apparent that one of the fingers may be removed or others may be added in a manner which will be apparent to one skilled in the art so that an opening of any polygonal or even circular aspect may be accurately reproduced whether by the discs or by the fingers, and if need be, interchangeably.

Manifestly, by suitable selection of discs 35 which are replaceable for said purpose, any diameter opening may be matched and selected and corresponding discs may be removably secured to the apparatus as by means of the wing nut 33 shown or the like.

Tubular elements like 70 can, of course, be substituted in various lengths as witness the replaceable and adjustable sleeve 98 and finger 99 of Figure 8.

This invention features an apparatus for projecting in plane outline a pattern for forming a conduit or the like between spaced openings, thereby accomplishing within a relatively short time, as a few minutes, a task heretofore frequently requiring several hours, or which was not susceptible of successful accomplishment by persons not skilled in pattern projection, geometry, allied arts or not otherwise skilled and experienced.

While I have herein shown and described my invention in what I have conceived to be the most practical and preferred method and embodiment, it is recognized that departures may be made therefrom within the scope of my invention, which is not to be limited to the details disclosed herein but is to be accorded the full scope of the claims so as to embrace any and all equivalent devices.

Having thus described my invention, what I claim as new and desire to secure by Letters Patent is:

1. A pattern former comprising a longitudinally adjustable supporting arm, pattern shaping members replaceably secured on said arm at longitudinally spaced points and extending laterally therefrom defining a plane transverse to the axis of said arm, and means associated with said arm and shaping members for establishing and maintaining a desired degree of angularity between said arm and said members, said pattern shaping members comprising a pair of radially disposed base members pivotally connected for angular adjustment relative to one another

on an axis co-incident with the axis of said arm, said base members having threaded end portions, individual tubular elements having threads for engagement with said end portions, individual fingers designed to telescope with respective tubular elements, and chuck elements on said tubular elements to hold said fingers in a selected position of extension from said tubular elements.

2. A pattern former comprising a longitudinally adjustable supporting arm, pattern shaping members replaceably secured on said arm at longitudinally spaced points and extending laterally therefrom defining a plane transverse to the axis of said arm, and means associated with said arm and shaping members for establishing and maintaining a desired degree of angularity between said arm and said members, said pattern shaping members comprising a pair of radially disposed base members pivotally connected for angular adjustment relative to one another on an axis co-incident with the axis of said arm, said base members having threaded end portions, individual replaceable tubular elements having threads for engagement with said end portions, individual replaceable fingers designed to telescope with respective tubular elements, and chuck elements on said tubular elements to hold said fingers in a selected position of extension from said tubular elements.

3. A pattern former comprising a longitudinally adjustable supporting arm, pattern shaping members at least one of which is substantially X-shaped replaceably secured on said arm at longitudinally spaced points and extending laterally therefrom defining a plane transverse to the axis of said arm, and means associated with said arm and shaping members for establishing and maintaining a desired degree of angularity between said arm and said members, said X-shaped pattern shaping members comprising oppositely directed pairs of laterally extensible fingers angularly adjustable relative to each other on a common central pintle within said plane to establish selected points of a plane figure.

4. A pattern former as characterized in claim 3, each of said pattern shaping members having a central unthreaded opening, said supporting arms having an end extending loosely through said opening, abutment means at the outer end of the supporting arm, and a clamping means threadably engageable with the supporting arm, spaced inwardly therefrom and designed for selectively clamping the pattern shaping member between said clamping means and said abutment for holding the pattern shaping member in a desired position of rotative adjustment.

5. A pattern former as characterized in claim 4 in which one pattern shaping member is substantially disk-shaped.

6. A pattern former comprising a longitudinally adjustable supporting arm, pattern shaping members replaceably secured on said arm at longitudinally spaced points and extending laterally therefrom defining a plane transverse to the axis of said arm, and means associated with said arm and shaping members for establishing and maintaining a desired degree of angularity between said arm and said members, said pattern shaping members comprising oppositely directed pairs of laterally extensible fingers angularly adjustable relative to each other within said plane to establish selected points of a plane figure, and replaceable scribing tips secured in the ends of said fingers, said pattern shaping members including cross members having adjacent comple-

mentary recesses formed therein in nested relationship to one another and the sides of said recesses being spaced relative to one another to limit relative rotation of said members to 90°, sides of said cross members forming abutments for retaining said members in a desired parallel relationship.
